CAMPBELL SCOTT, OF YONKERS, NEW YORK, ASSIGNEE TO OTIS ELEVATOR COMPANY,
OF JERSEY CITY, NEW JERSEY, A CORPORATION OF NEW JERSEY.

MAGNETIC TRACTION-WHEEL DRIVE.

948,381.

Specification of Letters Patent.

Patented Feb. 8, 1910.

Application filed December 16, 1905. Serial No. 291,978.

To all whom it may concern:

Be it known that I, CAMPBELL SCOTT, a citizen of the United States, residing in the city of Yonkers, in the county of Westchester and State of New York, have invented a new and useful Improvement in Magnetic Traction-Wheel Drives, of which the following is a specification.

My invention relates to traction drive elevators, and one of its objects is the provision of simple and efficient means for varying the magnetic attraction between the drive wheel and the hoisting rope or ropes.

More particularly it is the object of the present invention to provide means for decreasing the strength of a magnetic friction drive wheel after the elevator has been started and again increasing the strength of the same upon stopping.

Other objects of the invention will appear hereinafter, the novel combinations of elements being pointed out in the claims.

In the accompanying drawings, Figure 1 represents more or less diagrammatically an elevator system with my invention applied thereto; Fig. 2 represents a side view, partly in section, of the magnetic traction wheel; and Fig. 3 is a plan view, partly in section, of the wheel shown in Fig. 2.

In Fig. 1, C designates an elevator car connected by means of ropes 2 of magnetic material to the counterweight W. These ropes pass upwardly from the car to and over the overhead sheaves 3 and 5, and thence downwardly under the traction wheel T. The ropes pass upwardly from the wheel T to and over the sheaves 5' to the counterweight W. In this instance, I have shown the sheaves 3 and 5 mounted on the overhead beam 4 and the sheave 5' on the beam 4'. The particular arrangement of the sheaves and their number may be varied as desired, but by the use of a magnetic traction wheel a smaller number is required and there will be less wear on the ropes due to bending. If desired, the beams 4, 4' may be in the same plane or the sheaves 3, 5' may be mounted on opposite sides of the beam 4. In most instances, at least three direction sheaves must be used as shown but by reason of the magnetic feature of the drive wheel T no additional sheaves near this wheel are required to secure necessary friction, and this is a great advantage as the

wear on the rope due to bending is greatly lessened.

M designates an electric motor which may be of any desired type, but I do not wish to be restricted to an electric motor as means entirely mechanical could be used as well for transmitting power to the drive wheel T, in which case the winding of the latter could be excited independent of any motor circuits.

S designates a manual switch in the car C which when moved in one direction or the other will operate either of the reversing switches R or R' and either auxiliary switch X or X' to effect the desired operation of the car. For instance, if the lever S2 is moved to the right it will first engage the fixed contact strip 16 and thereafter the contact strip 83 or both of said strips may be engaged at the same time. A circuit is thus closed from the positive main to and through the main line switch L, wires 18, 19, 86, solenoid 20', wire 21, contact strip 83, lever S2, wires 22, 23 and 24 to the negative main. The switches R' and X' will thereupon be closed and the motor circuits completed. The circuit through the armature extends through the wires 18 and 19, contacts 25, 26, wires 27, 28, 29, brush 30, armature 32, brush 31, wire 33, starting resistance 8, wire 34, contacts 35, 36, wires 37, 38, 24 to the negative main; while the circuit through the shunt field is completed from the positive main through the wire 18, contact 38, contact plate 39, contact 40, wire 41, motor terminal 42, shunt field coil (not shown), terminal 43, wires 86, 24 to the negative main. It will thus be seen that the switch R' closes the armature circuit while the auxiliary switch X' closes the field circuit. The car switch also closes a shunt circuit through wires 87 and 50, terminal 51, winding 63 of the wheel T, terminal 53, wire 54, contacts 88, 90 and bridge piece 58, wire 91, contact strip 16, lever S2, wires 22, 23, 24 to the negative main. Both the shunt field coil and the traction wheel winding are thus connected directly across the mains and maximum current flows through the latter.

The traction wheel T may be made in various ways, that herein shown being that disclosed and claimed in an application filed by David L. Lindquist, Serial No. 291,979, pending herewith. This particular traction wheel is shown here merely by way of illus-

tration. That disclosed in another co-pending application by August Sundh, filed December 16, 1905, Serial No. 291,986, could also be used if desired.

5 The main object of my invention is to lessen the consumption of current necessary for energizing the traction wheel. I therefore provide means for strongly magnetizing said wheel when the motor is started and 10 also when it is slowed down to a stop. In this instance, I associate a resistance with the accelerating apparatus so the former may be automatically inserted in circuit with the winding 63 after the motor has attained 15 a predetermined speed. Upon slowing down the motor prior to stopping, this resistance is automatically cut out to again increase the magnetic strength of the wheel.

Referring to Figs. 2 and 3, it will be seen 20 that the drive wheel T is made up of two sections or halves suitably secured together as by means of bolts and nuts after the winding 63 has been put in place in circular recesses near the periphery of the wheel.

25 60 designates the hub and 61, 61' the web portion of the wheel.

66, 66' designate the rim flanges for preventing the ropes from running off, while 67 30 are grooves for the ropes to prevent them from running over each other.

Each section is provided with a plurality of lateral projections 64, 64' with predetermined spaces between them to allow the halves to be put together dove-tail fashion 35 but leaving zig-zag air gaps between the projections of one half and those of the other. When the winding 63 is excited with electric current, the sections are oppositely polarized, as the wheel is in reality an elec- 40 tromagnet and the projections are in effect alternate north and south poles. If desired, the air gaps may be filled with some non-magnetic material, as, for example, wood, brass or Babbitt metal, etc., so as to make a 45 solid wheel. Furthermore, the grooves 67 may be cast with the sections or they may be turned after the wheel has been assembled.

Secured to one end of the hub 60 I have 50 shown a ring 53 of insulation on which are mounted two slip rings 73 and 81 connected to the terminals of the winding 63. Suitable insulated and spring-pressed brush holders 72 and 51 are supported by the bracket 69 which extends upwardly from the bearing 71 at the upper end of the standard 55 70. These brushes are adapted to slide on the slip rings 73 and 81 to convey current through wires 87 and 50 to the winding 63 and thence out through the wire 54 and 60 other connections to the negative main.

The accelerating magnets A are connected 65 in series with each other in a circuit between the points 55 and 92, which is directly across the armature. A fixed bar 57 may be provided with screws 56 to form adjustable

stops to limit the downward movement of the cores of the accelerating magnets. This arrangement effects a successive lifting of said cores so that the sectional resistance 8 shall be gradually cut out by the switches 70 operated by the accelerating magnets. The switches in this instance comprise bridge pieces 58 rigidly connected to the cores to move therewith, and also fixed contacts 59 connected at various points to the resistance 8 75 8. Any other means than that shown for successively operating the switches may be employed if desired.

When the last bridge piece 58 of the series is lifted the resistance 85 is inserted in the 80 circuit containing the winding 63 of the traction wheel T, said resistance being connected between the contacts 88 and 90. This resistance may be so designed as to obtain any desired reduction of current in the wind- 85 ing 63.

It is evident that by reason of the inertia of the various moving parts more power is required in starting and stopping than when the car is under way. In order to secure 90 sufficient friction and adhesion of the ropes to the friction drive the magnetism should be great enough to prevent slipping at any time during the operation of the elevator apparatus. And to economize current and thus 95 make the system more efficient I reduce the magnetism of the traction wheel after being started to full speed but increase it again in slowing down before stopping. For the sake of simplicity, I have omitted in the drawings any brake apparatus in connection with the car, sheaves or motor shaft. These could also be supplied as desired but the system, if properly designed, may depend entirely on the increased magnetism of the traction 100 drive wheel in bringing the moving parts to a stop. In order to stop the elevator car gradually there may be a plurality of resistances such as that indicated 85, which may be inserted one after another and also 110 successively cut out by any approved means.

For example, an additional set of contacts similar to those designated 88 and 90 could be arranged under the bridge piece to the left of that designated 58 at the extreme 115 right and an additional resistance 85 connected to these contacts. In such case when the switch in the car is brought to its intermediate or slow-down position, the motor circuits would be interrupted but the lever 120 82 would still be on the strip 16 or 17. The accelerating magnets would be deenergized and their cores would drop back to original position and those at the right would effect the cutting out of the resistance 85. The 125 magnets at the right may have the downward movement of their cores retarded in varying amounts so that the resistances 85 would be cut out step-by-step.

Without limiting myself to the precise con- 130

struction of details or arrangement of parts, what I claim and desire to have protected by Letters Patent of the United States is:

1. In an elevator, the combination with a car and hoisting cable, of a magnetic sheave, a motor for driving said sheave, and means controlled by a single device for supplying electric current to said motor and said sheave through different circuits and from a common source of supply. 70
2. In an elevator, the combination with an elevator car, counterweight and hoisting cables, of a magnetic sheave associated with said cables, a single device in the car, and means controlled by said single device for effecting the supply of current to said motor and sheave from a source of current supply independent of the motor. 75
3. In an elevator, the combination of an electro-magnetic sheave, and means for automatically inserting resistance in circuit with the windings of said sheave. 80
4. In an elevator, the combination with a car and its motor, of a magnetic sheave connected to be driven by said motor, one or more hoisting cables connecting the car to said sheave, and means controlled from the car for supplying current to the motor and sheave through different circuits supplying current independently of the motor and thereby effecting the energization of the sheave and the operation of the motor. 85
5. In an elevator, the combination with a magnetic sheave, of driving means therefor, and means controlled by a single device for supplying current to the sheave and driving means through separate circuits, and thereby effecting the application of power to said sheave and driving means, the current to said sheave being supplied from a source independent of said driving means. 90
6. In an elevator, the combination with a magnetic traction sheave, of a motor for driving the same, and means for automatically decreasing the magnetism of the sheave after the motor has started, and again increasing it before stopping. 95
7. The combination with an electro-magnetic traction sheave, of a motor for driving the same, and means for controlling the application of current to the winding of said sheave to effect different values of magnetism in said sheave varying in accordance with the tractive power required at starting, stopping and intermediately. 100
8. In an elevator, the combination with a car and its motor, of a counterweight for the car, one or more hoisting cables connecting the car and counterweight, a magnetic traction sheave connected between said motor and said cables, and automatic means for varying the magnetism of the entire sheave in accordance with variations in the tractive power required by said sheave. 110
9. In an elevator, the combination with a car, of a motor, a magnetic sheave connected to said motor, one or more cables of magnetic material connecting the sheave and car, and means for reducing the current consumed by said sheave after the car has attained a predetermined speed. 115
10. In an elevator, the combination with a motor, of a magnetic traction drive wheel driven thereby, a car and counterweight, one or more cables connecting the car and counterweight and passing around said drive wheel, and automatic means for simultaneously varying the magnetism of all parts of the wheel to correspond with variations in the tractive power required by said wheel. 120
11. In an elevator, the combination with a car, of a motor, a magnetic sheave connected to be driven by the motor, one or more ropes or cables connecting the sheave and car, means for energizing said sheave upon starting the motor, and means coacting with said energizing means for decreasing the energization of said sheave after the car has attained a predetermined speed. 125
12. In an elevator, the combination with a car, counterweight and connecting cables, of a motor, a magnetic sheave connected to be driven by said motor and associated with said cables to transmit motive power to the same to hoist or lower the car, means for energizing said sheave upon starting the motor, and means for partially deenergizing said sheave after the motor has attained a predetermined speed. 130
13. In an elevator, the combination with a car, counterweight and connecting cables, of a motor, a magnetic sheave driven by said motor and associated with said cables to drive the same, motor-controlling means, and automatic means associated with said motor-controlling means for simultaneously variably energizing the entire sheave to correspond with the duty required of said wheel. 135
14. In a traction elevator, the combination with a car, counterweight and connecting cables, of a motor and a magnetic sheave for driving said cables to hoist or lower the car, and motor-controlling means for partially deenergizing said sheave to lessen the consumption of current while the motor runs at substantially full speed. 140
15. In a traction elevator, the combination with a car, of a motor, a magnetic sheave connected to said motor, cables of magnetic material connecting said car and sheave, motor-controlling means, and means controlled from the car for effecting the energization of said sheave before the operation of said motor-controlling means. 145
16. In a traction elevator, the combination with a car, counterweight and connecting cables, of a motor, motor-controlling means, a magnetic sheave connected to be driven by said motor, means controlled from the car 150

for effecting the energization of said sheave, and means co-acting with said motor-controlling means for automatically reducing the current flow to said sheave after the motor has attained a predetermined speed.

17. In a traction elevator, the combination with a car, counterweight and connecting cables, of a motor, a sheave connected to be driven by said motor, means for strongly magnetizing said sheave upon starting and partially de-magnetizing same after the motor has attained a predetermined speed, and means co-acting with the aforesaid means for again strongly magnetizing said sheave 10 at or before slowing down said car to stop the same.

18. In a traction elevator, the combination with a car, counterweight and connecting cables, of a motor and sheave associated 20 with said cables, an electromagnetic winding or windings for said sheave, means for controlling the current flow to said winding to energize the sheave, and means for reducing the current flow to said winding 25 after the motor has attained a predetermined speed.

19. In a traction elevator, the combination with a car, counterweight and connecting cables, of a motor, an electromagnetic sheave 30 connected to be driven by said motor and

associated with said cables to transmit motive power to the same, means controlled from the car for strongly energizing said sheave upon starting and stopping the motor, a resistance, and automatic means for inserting said resistance in circuit with the electromagnetic sheave upon the motor attaining a predetermined speed.

20. In a traction elevator, the combination with a car, counterweight and connecting cables, of a motor, an electromagnetic sheave connected to be driven by said motor and associated with said cables to transmit motive power to the same to lift or lower the car, motor-controlling means, an opposition element, and means co-acting with said motor-controlling means for automatically inserting said opposition element in circuit with the electromagnetic sheave upon the motor attaining a predetermined speed and 40 automatically cutting out said opposition element upon slowing down the motor to stop the car.

In testimony whereof, I have signed my name to this specification in the presence of 55 two subscribing witnesses.

CAMPBELL SCOTT.
